APPARATUS FOR THREADING SEWING NEEDLES

David Robert Ligh, New Dorp, Staten Island, N. Y.

Substituted for abandoned application Serial No. 337,143, May 25, 1940. This application April 11, 1941, Serial No. 388,135

15 Claims. (Cl. 223—99)

This application is a substitute for application, Serial No. 337,143, filed May 25, 1940.

This invention relates to needle threading apparatus and more particularly to a device to accomplish expeditiously the passing of a thread through the eye of a needle intended for hand sewing operations.

It may occur that certain people are precluded from engaging in gainful or useful hand-sewing activities because they are unable to accomplish the threading of a needle. This may be unfortunately the fact in the case of persons who, due to minor physical or nervous ailments, may be unable to hold their hands with sufficient steadiness to project a thread through the eye of a sewing needle. In such cases there may be no question either of the adequacy of the eyesight or of the physical capacity to achieve sewing of the finest textile material. Blind persons as well as those suffering with various degrees of impaired vision could also employ both gainfully and usefully a certain amount of time in rough, preliminary sewing, provided a plurality of successively threaded sewing needles were available to them. The above is particularly true in individual situations in which no other person is present to perform the needle threading operation. This invention contemplates a needle threading apparatus which tends to coordinate expeditiously a person's hands in the operation of passing a thread through the eye of a hand sewing needle such that it may be achieved entirely by a sense of touch.

A general object of this invention is to simplify the threading of a hand-sewing needle.

Another object is to accomplish such threading in a minimum time.

A further object is to co-ordinate a person's hands in such threading operation.

Still another object is to accomplish such threading operation in an expeditious manner.

Still another object is to avoid splitting a thread in such threading operation.

In a preferred embodiment the invention comprises a standard whose uppermost end terminates partly in a horizontal plane and partly in a stepped portion which latter portion embodies a vertical radial slot. Disposed substantially coaxially with the standard in the uppermost horizontal terminating plane and in the plane of the slot but in spaced relation with regard to the latter is an elongated thread holder whose uppermost end embodies an extension which is positioned in the direction of the radial slot and in the plane thereof. In operation, the thread

holder is initially projected through the eye of a needle to be threaded and a thread looped about the thread holder. Thereafter, the needle is removed from the thread holder while the thread remains secured thereto. This serves to pass the thread through the eye of the needle.

A feature of the invention provides for an expeditious passing of a sewing thread through the eye of a needle with equal facility by persons having unsteady hands and/or impaired vision. Another feature involves coordination of movements of the hands during the threading operation. Still another feature tends to obviate the splitting of threads during the threading operation. A further feature enables both relatively thick and fine thread to be projected through the eye of a needle substantially with equal facility. A still further feature enables the accomplishment of threading entirely by touch of the hands.

This invention will be readily understood from the following description taken together with the accompanying drawings in which:

Fig. 1 is a perspective view of the preferred embodiment of the invention;

Fig. 2 is a cross-section of Fig. 1;

Fig. 3 is a fragmentary view of Fig. 1;

Figs. 4 through 7 illustrate the action which may be achieved by Fig. 1;

Fig. 8 is a fragmentary perspective view of another embodiment of the invention; and

Fig. 9 is a fragmentary perspective view of still another embodiment of the invention.

In the following description, the same reference numerals are employed to point out identical elements appearing in the several figures of the drawings.

Referring to Figs. 1 and 2 a base 15 comprises a hollow conical member 16 which has a horizontal table 17 disposed in the uppermost portion thereof and enclosed by a peripheral border 18 which is an integral extension of the member 16. Positioned on the table portion is a cushion 19 whose function will be hereinafter explained. Disposed centrally and vertically of the base is a conical standard 20 which is preferably fastened thereto by a screw 20S and whose uppermost end terminates partly in a horizontal plane 22 and partly in a stepped segmental portion 23, Fig. 3, having a slot 24 projecting vertically relative to the terminating plane 22 and extending radially relative to the standard 20. The lowermost portion of the slot 24 is coincident with the terminating plane 22 of the standard 20. It is ob-

vious that the base and standard may comprise a unitary structure.

Disposed substantially coaxially with the upper end of the standard 20 and projecting from the terminating plane 22 in the vertical plane of the slot 24 is a thread holder 25 comprising an elongated portion 26, Fig. 3, one end of which is positioned on the standard in a manner that will be hereinafter described and the opposite end of which carries an integral extension 27 which is disposed in the direction of the slot 24 in the vertical plane thereof. The thread holder 25 is preferably spaced from the slot 24. In another aspect the thread holder 25 may be considered as embodying a cut-out 28 extending vertically of the side thereof adjacent the slot 24 and positioned in the vertical plane embodying both the thread holder 25 and the slot 24 and opening in the direction of the slot 24. The lowermost portion 29 of the extension 27, which portion is also coincident with the uppermost portion of the cut-out 28, lies in a plane which is preferably parallel with the terminating plane 22 of the standard 20 but is disposed thereabove. It is to be noted that the extension 27 is disposed above the plane of the lowermost portion of the slot 24, which as previously mentioned, is coincident with the terminating plane 22. Thus, the thread holder 25 and slot 24 lie in coincident vertical planes.

The thread holder 25 is initially and suitably mounted centrally of a convenient metallic insert 30, Fig. 2, which may thereafter be pressed into the upper end of the standard 20 such that the thread holder 25 is mounted substantially in a coaxial relation therewith. It is to be understood that the thread holder 25 and associated slot 24 may be spaced relative to each other on the upper end of the standard in any manner that will tend to effect expeditiously a threading operation in a manner which will be presently described.

In the operation of Fig. 1, a needle 35 to be threaded is grasped at the pointed end between two fingers of one hand and disposed longitudinally in the slot 24 such that the eye thereof is passed over the thread holder 25 as shown in Fig. 4. Next, a thread 36 grasped between two fingers of the other hand is looped about the thread holder 25 as shown in Fig. 5. Thereupon, the needle pivoted at end 37 of the slot 24, Fig. 6, is actuated in a clockwise direction while at the same time the thread is pulled taut on the thread holder. As the eye of the needle commences to pass over the extension 27, the thread will be pressed against the lowermost portion 29 thereof and thus held until the eye of the needle has passed completely over the extension 27, or, in other words, until the eye of the needle has been withdrawn from the thread holder 25. Such actuation of the needle and such holding of the thread 36 serves to effect a passing of the looped end of the latter through the eye of the needle as shown in Fig. 6. Thereafter, while the thread is still taut, the needle 35 is elevated substantially horizontally to the position illustrated in Fig. 7. Now, the looped portion 38 of the thread 36 extending through the eye of the needle may be adjusted in the needle in a single or double manner depending on the nature of the contemplated sewing operation. Although the pivot 37, Fig. 6, tends to facilitate the hereinbefore method of threading a needle, it is obvious that such pivot may be dispensed with in certain

cases, depending on the size of the needle to be threaded and the expertness of the operator.

Fig. 8 is similar to Fig. 3 except in the respect that radial slot 40 lies in a plane which is parallel with the horizontal terminating plane 22 of the upper end of the standard 20 and the plane of the lowermost portion 29 of the extension 27 of the thread holder 25 but is disposed intermediate both of the latter planes. Accordingly, the extension 27 of the thread holder 25 is disposed above the plane of the lowermost portion of the slot 40. In operation, a needle 41 to be threaded is actuated in a counter clockwise direction on a pivot 42 which is the forward or lefthand terminal of the slot 40, such that thread holder 25 is projected through the eye of the needle. A thread is then looped about the thread holder 25 as described and shown above in connection with Fig. 5. Thereafter, the needle 41 is actuated in a clockwise direction on a pivot 43, which is the rearward or righthand terminal of the slot 40, until the position illustrated by the broken line 44 is attained. Such actuations of the needle serve to pass a looped portion of a thread through the eye of the needle in a manner similar to that aforementioned with regard to Figs. 4 through 7, and particularly Fig. 6. A feature of Fig. 8 is embodied in the pivots 42 and 43 both of which tend to facilitate the threading operation.

Fig. 9 illustrates an embodiment in which the uppermost end of the standard 20 terminates substantially in a horizontal plane, not shown, which is substantially identical with the plane 22, Fig. 1, and on which is suitably disposed a cylindrical cap 50 having a configuration which is readily accommodated to the uppermost end of the standard 20. Secured to this cap in a suitable manner is a thread holder 51 whose configuration and disposition are substantially identical with those of the thread holder 25, Fig. 3. Also suitably mounted on the cap is a pair of angle members 52, 52 disposed oppositely to each other so that a radial space 53 intervenes therebetween and is disposed in the vertical plane of the thread holder 51. In the radial space 53 is a member 54 positioned in parallel relation with respect to the previously mentioned uppermost terminating surface of the standard 20 and a lowermost portion 55 of an integral extension 56 formed on the uppermost end of the thread holder 51. The modification illustrated in Fig. 9 provides a structure which is essentially identical with the structure of Fig. 8, and which is utilized to pass a thread through the eye of a needle in the manner hereinbefore described in connection with Fig. 8. It is to be understood in Fig. 9 that the horizontal element 54 may be omitted so as to provide a structure which is substantially the same as that shown in Fig. 3.

The broken lines 60 shown in Fig. 1 outline a thimble which may be disposed on the standard 20 so as to be available readily for sewing purposes, and at the same time to protect the thread holder 25 or 51 against damage during periods of non-use. The cushion 19, Fig. 1, provides a convenient means for maintaining readily available different types of needles, or similar needles having different types of thread.

It is to be understood that the invention in its several embodiments as herein disclosed is readily capable of other modifications by those skilled in the art, and therefore is to be limited by the scope of the appended claims.

What is claimed is:

1. A needle threading apparatus comprising in combination supporting means, means disposed on one portion of the uppermost end of said supporting means and having an effective radial slot extending vertically relative to the uppermost end of said supporting means, and thread holding means mounted on another portion of the uppermost end of said supporting means in the plane of said slot and spaced from said slotted means.

2. A needle threading apparatus comprising in combination supporting means, means positioned on one portion of the uppermost end of said supporting means and having a slot extending radially and vertically with reference to the uppermost end of said supporting means, elongated means fastened to another portion of the uppermost end of said supporting means in the plane of said slot and spaced from said slot means, and an extension disposed on the uppermost end of said elongated means in the direction of said slot and in coincident planes embodying both said slot and said elongated means and spaced from said slot means.

3. A needle threading apparatus comprising in combination a base, a standard positioned on said base, a segmental projection formed on a portion of the uppermost end of said standard and having a radial slot extending vertically relative to the uppermost end of said standard, elongated means disposed on a different portion of the uppermost end of said standard in the plane of said slot and in spaced relation with reference to said projection, and an extension mounted on the uppermost end of said elongated means in the plane embodying both said slot and said elongated means and spaced from said slotted projection.

4. A needle threading apparatus comprising in combination upright means, a stepped portion formed integrally on a segment of the uppermost end of said upright means, said stepped portion having a radial slot extending vertically with reference to the uppermost end of said upright means, elongated means mounted on a different segment of the uppermost end of said upright means in the plane of said slot and spaced from said stepped portion, and an extension integral with the uppermost end of said elongated means and disposed in the direction of said slot in coincident planes embodying both said slot and said elongated means and in spaced relation with reference to said stepped portion.

5. A needle threading apparatus comprising in combination supporting means, elongated means mounted vertically on a substantially central portion of the uppermost end of said supporting means, an integral extension disposed on the uppermost end of said elongated means in the plane thereof, and means projecting from a different portion of the uppermost end of said supporting means in spaced relation with reference to both said elongated means and said extension and having a radial slot which is disposed vertically with reference to the uppermost end of said supporting means in the plane embodying both said elongated means and said extension.

6. A needle threading apparatus comprising in combination supporting means, an elongated member disposed vertically on a substantially central portion of the uppermost end of said supporting means and having a cut-out, and means having a slot and mounted on another portion of the uppermost end of said supporting

means in spaced relation with reference to both said elongated member and cut-out such that said slot is disposed radially and vertically relative to the uppermost end of said supporting means in alignment with both said elongated member and cut-out.

7. A needle threading apparatus comprising in combination supporting means whose uppermost surface terminates substantially in a horizontal plane, a segmental projection extending vertically from a portion of said terminating plane and having a radial slot which extends vertically relative to said terminating plane and whose lowermost portion is coincident with said terminating plane, elongated means mounted on another portion of said terminating plane in the plane of said slot, and an extension affixed to the uppermost end of said elongated means in spaced relation with regard to said slot and in the direction of said slot and in a plane embodying both said slot and said elongated means and disposed above said lowermost portion of said slot.

8. A needle threading apparatus comprising in combination supporting means whose uppermost end terminates substantially in a horizontal plane, means extending vertically from a portion of said terminating plane and having a radial slot which extends vertically relative to said terminating plane and whose lowermost portion lies in said terminating plane, elongated means extending from another portion of said terminating plane in the plane of said slot and in spaced relation with regard to said slot, and an extension affixed integrally to the uppermost end of said elongated means and disposed in the direction of said slot and in the plane of said slot such that said extension lies above said lowermost portion of said slot.

9. A needle threading apparatus comprising in combination supporting means whose uppermost surface terminates substantially in a horizontal plane, elongated means mounted vertically on one portion of said terminating plane, an extension disposed horizontally on the uppermost end of said elongated means such that the lowermost portion of said extension lies in a plane which is substantially parallel to said terminating plane and which is disposed thereabove, and means extending vertically from another portion of said terminating plane and having a radial slot which is disposed in the plane of both said elongated means and extension in spaced relation with regard to both thereof such that the lowermost portion of said slot lies in a plane which is substantially parallel with said terminating plane and the plane of the lowermost portion of said extension and which is positioned intermediate both said latter planes.

10. A needle threading apparatus comprising in combination upright means whose upper surface terminates in a horizontal plane, a projection integral with said upright means and extending vertically from a portion of said upper terminating plane, said projection having a slot which extends radially and vertically relative to said upper terminating plane and whose lowermost portion lies in a plane which is parallel to said upper terminating plane and which is disposed thereabove, elongated means mounted on said upright means and projecting from another portion of said upper terminating plane in the vertical plane of said slot, and an extension mounted on the uppermost end of said elongated means in the direction of said slot and the vertical plane of said slot and in spaced relation

with regard thereto such that said extension is disposed above the plane of the lowermost portion of said slot.

11. A needle threading apparatus comprising in combination a base, a standard disposed on said base and whose uppermost end terminates substantially in a horizontal plane, an element disposed on a portion of the uppermost end of said standard, said element having a slot extending both radially and vertically relative to said terminating plane and whose lowermost portion lies in a plane which is substantially parallel to said terminating plane and which is located thereabove, and a member having one end formed with a cut-out and disposed vertically on another portion of the uppermost end of said standard in spaced relation with regard to said element such that said cut-out is located on the edge of said member nearest to said slotted element and lies above the plane of the lowermost portion of said slot.

12. A needle threading apparatus comprising in combination a standard and means mounted on said standard to pass a thread through the eye of a needle, said thread passing means comprising means disposed on the uppermost end of said standard to provide a radial slot, said slot having a lowermost portion which is disposed above the uppermost end of said standard, an elongated element positioned on the uppermost end of said standard in the plane of said slot and spaced from said slot, and an extension affixed to the uppermost end of said element in the direction of said slot and in a plane embodying both said slot and said elongated element and disposed above the lowermost portion of said slot.

13. A needle threading apparatus comprising means whose uppermost surface terminates sub-

stantially in a horizontal plane, means disposed on one portion of said terminating plane and embodying a slot extending radially and vertically with reference to said terminating plane and whose lowermost portion lies in a plane which is substantially parallel to said terminating plane and which is disposed thereabove, and elongated means disposed on another portion of said terminating plane in the plane of said slot and spaced from said slot means.

14. A needle threading apparatus comprising means whose uppermost surface terminates substantially in a horizontal plane, means extending vertically from one portion of said terminating plane and having a slot extending radially and vertically with reference to said terminating plane and whose lowermost portion is coincident with said terminating plane, and elongated means extending from another portion of said terminating plane in the plane of said slot and spaced from said slot means.

15. A needle threading apparatus comprising upright means, and means attached to said upright means to pass a thread through the eye of a needle, comprising means mounted on the uppermost surface of said upright means and terminating substantially in a horizontal plane, means disposed on one portion of said terminating plane to provide an effective slot extending radially and vertically with reference to said terminating plane and whose lowermost portion lies in a plane which is substantially parallel to said terminating plane and which is disposed thereabove, and an elongated member positioned on another portion of said terminating plane in the plane of said slot and spaced from said slot means.

DAVID ROBERT LIGE.
